EMBROIDERY FLOSS HOLDER

Georgia J. Marshall, Pocatello, Idaho

Application April 29, 1957, Serial No. 45,922

Term of patent 14 years

(Cl. D3—19)

FIG. 1.

FIG. 2.

FIG. 3.

FIG. 4.

FIG. 5.

Fig. 1 is a perspective view of an embroidery floss holder, showing my new design as it appears with the underlying drawer in open position;

Fig. 2 is a top plan view thereof as it appears with the drawer in closed position and the spindle rotating handle separated from the holder;

Fig. 3 is a rear elevational view;

Fig. 4 is a left end elevational view of the embroidery floss holder shown in Fig. 3; and

Fig. 5 is a right end elevational view thereof.

I claim:

The ornamental design for an embroidery floss holder, substantially as shown.
